UNITED STATES PATENT OFFICE

WILLIAM H. BEAN, OF OAKLAND, CALIFORNIA

AUTOMATIC WORK GRIPPER

Application filed June 29, 1931. Serial No. 547,745.

My invention relates to improvements in automatic work grippers and it consists in the combinations, constructions and arrangements hereinafter described and claimed.

In the present state of the art, boards, planks and timber generally when manually moved for sawing are gripped by the fingers of a workman. This practice presents many inconveniences, especially when moving heavy boards, and there always exists the danger to the workman of contacting slivers and in bringing his hands too close to the rotating saw. Time is also lost in moving the work into the path of the saw and then in moving the saw.

An object of this invention is to provide an automatic gripper which will automatically grip the work when the device is moved in one direction and which will disengage from the work when being moved in the opposite direction.

Another object of my invention is to provide a gripper which can be easily adjusted for gripping boards, planks, and the like of different sizes.

More specifically, the object of my invention is to provide a bar and a frame swingably attached to the bar, so arranged that when the bar is pulled in one direction the work is firmly held between the frame and the bar.

A further object of my invention is to provide a device which is extremely simple in construction and efficient for the purpose intended.

Other objects and advantages will appear as the specification proceeds and the novel features of the device will be particularly pointed out in the claims hereto annexed.

My invention is illustrated in the accompanying drawing forming a part of this specification, in which

Figure 1 shows the device in operation;

Figure 2 is a plan view of the device;

Figure 3 is a side elevation;

Figure 4 is an end elevation;

Figure 5 is a section along the line 5—5 of

Figure 2;

Figure 6 is a section along the line 6—6 of

Figure 3; and

Figure 7 shows a modified form of the device.

While I have shown only the preferred forms of my invention I wish it to be understood that various changes and modifications may be made within the scope of the appended claims without departing from the spirit of my invention.

In its preferred form my automatic gripper generally indicated at 1 comprises a bar 2 and a frame 3.

The bar 2 is of the form shown in Figures 2 and 3 and has one end fashioned into a handle 4. The other end of the bar has two lugs 5 which slidably carry pins 6 as shown in detail in Figure 6. Springs 7 yieldingly hold the pins 6 against cross-bars 8, the latter being slidably received in openings 9 disposed adjacent to the lugs 5.

The side walls of the openings 9 extend at an angle to the outer side of the bar 2 so that the sides of the openings and the outer side of the bar form stops 10 as shown in Figure 6.

The portions of the cross-bars 8 adjacent to the bar 2 are provided with teeth 11 on the sides facing the stops 10, and in cooperation with the latter serve for adjusting the effective length of the cross-bars 8.

A brace 12 connects the cross-bars 8 thus forming the frame 2. The brace 12 may carry short pins 13, which are adapted to be introduced into the timber as will be described later. In Figure 5 I show the brace 12 being swingably attached to one of the bars 8 by means of a screw 14 having a shank 15, which serves as a bearing for the brace 12. A shoulder 16 prevents the loosening of the screw 14 and allows a free rotation of the brace 12. A screw 14 for each bar 8 is provided.

The frame 2 is free to swing around the stops 10 to the left as shown in Figure 1, but the motion to the right is limited by the lugs 5. The brace 12 remains parallel to the bar 2 regardless of an angle between the cross-bars 8 and the bar 2. The distance between the brace 12 and the bar 2 grows smaller the farther to the left the frame 2 is swung.

From the foregoing description of the

various parts of the device the operation thereof may be readily understood.

Assume that an operator has to cut a board 17 into a number of smaller pieces of a predetermined size as illustrated in Figure 1. He adjusts a stop 18 in the proper position and then places the board 17 on a table 19. The operator then adjusts the gripper 1 so that the distance between the brace 12 and the bar 2 is slightly wider than the width of the board 17, and places the gripper over the board. The springs 7 will push the gripping frame 2 to the left, so that the pins 13 will contact with the side of the board. The operator pulls the handle 4 to the right. This movement will be relative to the brace 12 because the bars 8 will swing and will shorten the distance between the bar 2 and the brace 12. Further movement of the bar 2 will produce a gripping effect and the board 17 will be moved toward the stop 18.

The reverse movement of the bar 2 will swing the gripping frame 2 to the right until the bars 8 strike the lugs 5. The distance between the brace 12 and the bar 2 will increase to its maximum and the pins 13 will be freed from the work. The operator continues to move the gripper until a new position is reached. The board may be cut by a saw 20 after which the cut piece may be removed and the work gripper moved to the right until the work 17 again strikes the stop 18.

The bar 2 carries a pin 21 which is fastened thereto on approximately the same level as the cross bars 8. Normally it rests on the board 17. The pin 21 serves two purposes: first, it holds the handle 4 above the board 17 so that the operator may readily grasp it; and second, it makes both cross-bars 8 contact with the upper surface of the board, thus assuring the proper gripping effect.

In many instances an operator has to cut thousands of pieces of the same size. My automatic gripper allows the operator to move the boards, planks, and the like with speed and ease and eliminates the tiresome and dangerous process of hand gripping.

It is obvious that the pins 13 may be omitted because there will be sufficient friction between the brace 12 and the work to produce the gripping action.

It is obvious also that the frame 3 may be provided on the other side of the bar 2 or on both sides of the bar to take care of extremely wide boards. In that case the cross-bars 8 may be swingably secured to the bar 2 and the braces 12 may be adjustably secured to the cross-bars 8 as shown in Figure 7. The board then will be gripped between the two braces 12.

I claim:

1. A work gripper, comprising a bar and a frame swingably and adjustably secured

thereto, said frame having a brace adapted to engage with the work when the latter is gripped and yielding means for urging the brace into engagement with the work.

2. A work gripper, comprising a bar having openings disposed adjacent to one end of the bar and having the other end formed in a handle, a frame having cross-bars adjustably and swingably received in said openings, a brace connecting the cross-bars and cooperating with the bar for gripping the work and yielding means for urging the brace toward the bar for gripping work therebetween.

3. A work gripper, comprising a bar having openings disposed adjacent to one end of the bar and having the other end formed in a handle, a frame having cross-bars adjustably and swingably received in said openings, and a brace connecting the cross-bars and cooperating with the bar for gripping the work, and means urging the frame to be swung in one direction.

4. A work gripper, comprising a bar having one end fashioned into a handle and openings disposed adjacent to the other end of the bar, the walls of the openings extending at an angle to the bar so as to form angular stops, cross-bars having portions adjacent to the first bar serrated and received in the openings, means urging the serrated edges against the stops and a brace connecting the other ends of the cross-bars and cooperating with the bar for gripping the work.

5. A work gripper comprising a bar having one end fashioned into a handle, frames swingably attached to both sides of the other end of the bar, said frames adjustably carrying braces for gripping work therebetween and means for urging the frames in one direction, and yielding means for urging the braces toward each other.

6. A gripper for moving timber or the like comprising a reciprocal frame arranged for overlying a timber and yielding means for automatically moving the frame into gripping relation with the timber when the frame is moved in one direction and made to release the grip thereon when the frame is moved in the opposite direction, whereby the timber may be advanced step by step during successive reciprocating movements of the frame.

7. A work gripper comprising a bar adapted for being disposed alongside of a timber on one side of the latter, a frame swingably secured to the bar for overlying a face of the timber, a brace for gripping the opposite side of the timber from that of the bar, pins secured to the brace and adapted to engage with the timber, and yielding means urging the brace toward the bar.

8. A work gripper comprising a bar adapted for being disposed alongside of a

timber or the like on one side of the latter, a frame swingably secured to the bar for overlying a face of the timber, a brace for gripping the opposite side of the timber 5 from that of the bar, and yielding means for urging the brace toward the bar.

9. A work gripper comprising a substantially parallelogram-shaped frame having the sides thereof swingably secured together, 10 yielding means for urging the frame to partially collapse, and a handle extending from one of the frame sides.

10. A work gripper comprising a substantially parallelogram-shaped frame having 15 the sides thereof swingably secured together, yielding means for urging the frame to partially collapse, a handle extending from the frame, and a projection on the handle extending toward the frame side and serving 20 as a stop when the frame is applied to a timber or the like.
